UNITED STATES PATENT OFFICE.

JAMES L. ADAMS, JR., OF MILWAUKEE, WISCONSIN, ASSIGNOR TO A. O. SMITH CORPORATION, OF MILWAUKEE, WISCONSIN, A CORPORATION OF NEW YORK.

PERIODICALLY-VARYING-FREQUENCY MOTOR-GENERATOR SET.

Application filed November 17, 1919. Serial No. 338,464.

To all whom it may concern:

Be it known that I, JAMES L. ADAMS, Jr., a citizen of the United States, and residing in the city of Milwaukee, county of Milwaukee, and State of Wisconsin, have invented certain new and useful Improvements in Periodically-Varying-Frequency Motor-Generator Sets; and I do declare that the following is a full, clear, and exact description thereof, such as will enable persons skilled in the art to which the invention pertains to make and use the same, reference being had to the drawings hereto attached and forming part of my specification for disclosure as to the details of construction and explanation of the mode of operation.

The invention relates to means for generating alternating electric currents of periodically varying frequencies. It has particular reference to motor-generators which are used to supply electrical energy to motors driving machines or tools which must be operated intermittently and alternately in order to accomplish the purposes for which such machines or tools are employed.

In application Serial No. 212,934, filed January 21, 1918, by R. Stanley Smith, on which Patent No. 1,397,020, was granted November 15, 1921, to which reference may be had, there is disclosed an assemblage, the several machines of which by their connected and related movements perform in regular sequence the series of operations involved in the conversion of sheet metal plates or blanks into a completed and unitary frame for an automobile or other vehicle.

The assemblage referred to comprises machines which have for their dependent and related functions, among others, the punching of blanks from metal sheets or plates to form the side and end and cross bars of an automobile frame, piercing such blanks at predetermined places for the accommodation of the rivets employed to unite in one structure the several parts of the frame, shaping the blanks by flanging or offsetting so that the side and end and cross bars will have the necessary degree of rigidity, attaching brackets and gussets, machining or milling the several parts as required, assembling and clamping in correct relation the elements of the frame, inserting rivets, and riveting the assembled parts together while

clamped in their respective positions, so that a completed automobile or other frame is produced in its entirety and as a unitary structure by the operation of wholly automatic mechanical devices.

The machines constituting the said assemblage have periods of work alternating with periods of rest. During the work periods such machines are operated through part of a given time cycle to perform their allotted functions, upon the completion of which the machines assume positions of rest for the remainder of the cycle. Ordinarily, the periods of work of the machines and the alternating periods of rest will be of equal duration, but such periods may be varied each with relation to the other, according to the particular exigencies which may arise from time to time in differing constructions of work. The assemblage is also provided with conveyor devices the purpose of which is to convey or transfer the work from machine to machine in regular progression while the machines are at rest, the conveyor devices being at rest in the intervals between conveying movements and during the instants that the machines are performing their work operations.

My present invention has been especially constructed for the purpose of effecting the intermittent and alternating movements of the machines and conveyor devices above mentioned and disclosed in the patent hereinbefore referred to.

Such present invention has for its object the provision of a simple and efficient construction by means of which a plurality of alternating electric currents of periodically varying frequency can be generated. In generating such currents the periodically recurring frequency maxima of the several currents occur at different instants in any given period or time cycle, so that the maximum of frequency for the first current will occur at a different instant than that of the second current, and so on, through the whole series of currents, if more than two be employed. By this means, I am enabled to produce currents to drive a plurality of groups of electric motors in such a way that while one group of motors is functioning, another group of motors will be standing still, and vice versa. The groups of motors operate alternately, periodically and inter-

mittingly, in recurrent time cycles each of predetermined time length. But it will be understood that the motors of each of the separate groups are operated in synchronism, although the several groups are operated alternately and intermittently with relation to each other. By thus driving the motors, I am enabled to operate the connected machines and conveyor devices in the 10 described order, i. e., in alternating periods of work movement and periods of conveyor movement, each alternating with periods of rest.

I prefer to use induction motors with distributed windings on both elements, such as the wound-rotor type induction motor of commerce, and to supply alternating current of approximately constant frequency to the first element of the motor, which may be the 15 rotor, and current of varying frequency to the second element, which may be the stator, as disclosed in application Serial No. 315,189, filed August 4, 1919, by R. Stanley Smith and me as joint inventors. The current of constant frequency which is supplied to all of the motors of the several groups may be generated in a common source, but the currents of varying frequency which are supplied to the motors in the different 20 groups are each generated in an independent source, as in the application hereinbefore 25 last referred to.

The novel features of my present invention will be pointed out in the claims appended to this specification.

In the drawings which accompany this specification,

Figure 1 is a view, partly in section, illustrating diagrammatically a general construction embodying the invention, which latter will hereinafter be described in detail.

Fig. 2, illustrates a time-frequency chart, and is designed to show the relation, at successive time instants in the recurring time cycles or work periods, between the periodically varying frequency alternating currents, and a third current which may be one of approximately constant frequency.

Referring to the drawings, the numeral 1, 50 Fig. 1, indicates a double rotation synchronous motor, and 2 and 3 indicate alternating current generators, which latter are connected to and driven directly by the respective rotating elements of the motor 1, by the 55 shafts 4 and 5.

The shafts 4 and 5 are connected through the speed reducing pinions 6, 7, 8, 9, 10 and 11; gears 12, 13, 13^a, 14, 15 and 16, the shafts 20 and 21, and irregular or non-circular gears 17, 18 and 19, the purpose 60 being to transfer power from one end of the motor-generator set to the other. The shafts 4 and 5, above referred to extend in the same plane with their adjacent ends abutting, or substantially so. These shafts

are connected with each other, by means of trains of speed-reducing and accelerating pinions and gears, and other shafts and gears intermediate the said trains of pinions and gears. The particular connection shown 70

comprises pinions 6 and 9 upon the distant ends of the respective shafts 4 and 5, and engaging gears 12 and 14, respectively, the gear 12 being shown as an internal gear, for the purpose of securing the transmission 75

of motion in the necessary direction. The gears 12 and 14 are fixed or otherwise mounted on short shafts which are held or journaled in the frame, as the case may be, and are connected at their hubs with pinions 80

7 and 10, meshing with gears 13 and 15, the latter being likewise mounted upon short shafts having a bearing in the frame of the apparatus. The gears 13 and 15 carry 85

pinions 8 and 11, which latter engage gears 13^a and 15, mounted upon shafts 20 and 21, journaled in bearings which latter may depend from the frame. The shafts 20 and 21 are not aligned axially as are the shafts 4 90

and 5, previously referred to, but are arranged in parallel planes so that gears 17 and 19, mounted upon the ends of the said shafts may transmit the motion from one 95

shaft to the other through the medium of the said gears and the interconnecting gear 18, the purpose of this arrangement being to transfer power from one end to the other as stated before. While in the construction 100

illustrated, only as an example, I have shown the pinions and gears and irregular gears in the number and arrangement indicated, it is 105

obvious that a lesser number of such pinions and gears may be used to effect the purposes of my invention. The separate shafts 20 and 21 are shown as connected by the 110

irregular or non-circular gears 17, 18 and 19, but only two of such gears may be necessary in some cases.

With a view to overcoming or greatly reducing the stresses required to transfer power from one end of the motor-generator set to the other through the gearing described, I supplement the gears by two varying speed direct current machines, which 115

may be shunt wound and which function alternately as motors and as generators. These direct current shunt wound machines are indicated by the numerals 22 and 23, in 120

Fig. 1, and their rotors are mounted upon the shafts 4 and 5, respectively. When one is acting as a generator the other will act 125

as a motor, and vice versa, as will later be described. In addition, the two varying speed direct current machines 22 and 23, through the lines 25, are connected to the 125

emergency storage battery 24. This construction provides an arrangement which will permit of the operation of the entire set for a few minutes, as may be necessary during an emergency which may arise from 130

the interruption of the supply current which drives the main double rotation motor of the set.

At the left of Fig. 1, I have indicated by the numeral 32, the alternating current generator, which supplies a current of constant frequency through the power line 26, to one element of the double rotation synchronous motor 1. The other element of the motor 1, 10 is supplied with direct current through line 27, from the battery 24.

At 30 and 31, I have illustrated conventionally two groups of motors, each group of which may embrace any desired number 15 of motors wired in parallel, if a plurality of motors be employed in each group. The generators 2 and 3, through connections 28 and 29, supply alternating currents of varying 20 frequency to the first elements of the respective motors or groups of motors, 30 and 31. The second elements of the said motors or groups of motors are connected to the line 26, said connections supplying currents of constant frequency to the elements 25 mentioned.

The speeds of the main motor generator set 1, are held within the range of a 1:3 variation from maximum to minimum by means of the gearing 6 to 19, but the two 30 direct current machines 22 and 23, are wound for a 4:1 or a 3½:1 speed variation, the examples given in this last connection being merely typical and not necessarily 35 variable. Under these conditions, it will be evident that with full field strength on the direct current machines 22 and 23, they can be made to run not only at the lowest speeds required by the motor generator set 1, but can be made to act as direct current generators 40 at these speeds, while at the higher speeds they can in turn be made to function as direct current motors, if their fields are weakened to the opposite limit.

This strengthening of the field of the machine which is at a given moment operating at the lowest speeds, and weakening of the field of the direct current machine which at the same moment is operating at the highest speeds, is accomplished automatically. 45 The devices which I use for effecting the result described are constituted of a rheostat 35, which is connected to the shunt field circuit 36, of the direct current machines 22 and 23. Upon one end of the shaft 34 of the 50 gear 18, an eccentric or crank pin is mounted, which latter part operates a link 33, connected with the rheostat 35, so as to operate the latter. The eccentric or crank pin may be mounted upon any convenient low speed 55 shaft, instead of the shaft 34, as shown, and more than one rheostat 35, may be used, if desired.

The motors 30 and 31, are normally so connected that the magnetic field rotations of both stator and rotor are in the same di-

rection about their shafts as axes, and under these conditions the instantaneous speeds, in revolutions per second, will be given by the difference in frequencies in the two elements of each motor, divided by its 70 number of pairs of poles. Thus, the respective speeds for the two groups of motors, will vary from instant to instant in accordance with the vertical distance between curves 28' and 29' and the common base line 75 26', in Fig. 2, which distances give respectively the instantaneous difference in frequencies between the lines or circuits 28 and 26, and 29 and 26. It will be noted that at points 37 or 38, or at any other similarly situated points in the succeeding work periods, the motor speed will be zero.

From what has been hereinbefore stated respecting the arrangement, it will be evident that if the double rotation motor 1 is 85 of the self starting type, and is thrown onto line 26, or if a small amount of direct current is fed through suitable starting rheostats to the motors 22 and 23, the motor 1 will be brought up to synchronous speed, 90 which it will then retain, and the two generators 2 and 3, together with the two direct current machines 22 and 23, will subsequently rise and fall periodically in speed. This action will be determined primarily by the 95 particular instantaneous positions of the irregular gears, whatever may be the number of the latter, with the link 33 moving back and forth so as to cut in and out the resistance in the shunt fields of the direct current machines 22 and 23, in such exact timing as to cause them to endeavor to very slightly lead the speed changes in the main gear set, and consequently tend to practically relieve the latter of the load. 100

The torques exerted by both elements of the double rotation main driving motor 1, are exactly equal at any given instant, irrespective of the exact speeds at which these 110 two elements are operating at the moment. Therefore, at any given instant and for a given torque, the power developed by each element will vary in proportion to its speed of rotation. The two elements of the main driving motor will never develop exactly 115 equal powers, except when they are both running at the same speeds.

As a consequence of this condition, it is found in practice to be necessary to transfer power alternately from one end of the 120 motor generator set to the other. This result I accomplish by varying in a proper manner the resistances in the shunt field circuits of the two direct current machines 22 and 23, so that such machines will run at 125 the required speeds at all given points on each recurrent work cycle. The said direct current machines not only will work as described, but will also work as motor and generator, respectively, or vice versa, at 130

such points as may require material transfers of power from one end of the set to the other, in order to equalize the torques developed by the main driving motor 1 in its 5 two rotating elements.

Twice in each work period this transfer of power is reduced to zero, as the two generators 2 and 3 approach more or less the same speed. But at no time does such 10 power transfer reach a value equal to more than the instantaneous acceleration load plus 25% of the power output of the motor generator set, in the typical case which I have described as an example, and in which 15 the maximum and minimum speeds of the generators 2 and 3 have a ratio of 3:1.

The percentage of time of each work cycle or operating period, throughout which the generators 2 and 3 are operating at their 20 respective maximum and minimum speeds, will be dependent upon the particular shape of the irregular gears, 17, 18 and 19, for instance, which may be used at the time. As an example, I have shown an arrangement 25 of gears which will permit of the operation of the set at maximum and minimum speeds, each of which remains practically constant for about 30% of the total time of each work period; or a total of approximately 30 30 proximately 60% of constant speed operation, and 40% of varying speed operation, during each periodic and recurrent work cycle.

The foregoing constitutes a description of 35 a convenient and simple but effective embodiment of the means which I have invented for generating a plurality of alternating electric currents of periodically varying frequency, and in which the maximum frequency of one current occurs at a different time instant from that of the other, and which are to be employed to operate intermittently and alternately a plurality of groups of electric motors at varying speeds, 40 each of which groups may comprise a single motor, or a plurality of motors in parallel.

Modifications of the construction and arrangement described will occur to those skilled in the art to which the present invention relates, but it is to be understood that changes within the scope of the appended claims may be made without departing from the spirit of my invention.

Having thus described my invention, what I claim and desire to secure by Letters Patent of the United States, is:—

1. In a varying frequency generating set, a plurality of alternating current generators, and means for driving the said generators at speeds which periodically rise and fall in the alternately recurring periods, such means including a plurality of speed-reducing gear trains, whose high speed ends

are connected to said generators, and whose 65 low speed ends are interconnected.

2. In a varying frequency generating set, a plurality of alternating current generators, and means for driving the said generators, in combination with a plurality of speed-reducing gear trains, whose high speed ends are connected to said generators, and non-circular gears connecting the low speed ends of said speed-reducing trains. 70

3. In a varying frequency generating set, a 75 plurality of alternating current generators, and means for driving the said generators, in combination with a plurality of speed-reducing gear trains each composed of circular gears, the high speed ends of the trains connected to the generators, and the low speed ends interconnected by means of non-circular gears. 80

4. In a varying frequency generating set, a 85 plurality of alternating current generators, means for driving the same, and other means for controlling the said generators at speeds which periodically rise and fall in such manner that their instants of maximum speed alternate in the recurring periods, said other 90 means comprising a plurality of speed-reducing gear trains inter-connecting the said generators.

5. Two alternating current generators with means for driving the same, a speed-reducing gear train connected to each generator, and a set of irregular or non-circular gears connecting the said gear trains. 95

6. In a varying frequency generator set, a 100 plurality of alternating current generators and means for driving the same, speed-reducing gear trains connecting the said generators, such gear trains being inter-connected at their low speed ends by irregular or non-circular gears, in combination with a 105 plurality of varying speed direct current machines, one for each generator, to supplement the action of the said gear trains, and means for driving the said direct current machines as described. 110

7. In a varying frequency generator set, a plurality of alternating current generators, and means for driving the same, in combination with a plurality of speed-reducing gear trains connected at their high speed ends to the generators and at their low speed ends by irregular or non-circular gears, a plurality of lines of motors, one element of each motor being supplied with current of varying frequency by the generators, and 120 means for supplying current of constant frequency to the other element of each motor.

8. In a varying frequency generator set, two alternating current generators, a double 125 rotation motor for driving such generators at varying speeds which periodically rise and fall in alternately recurring periods,

and including in the combination connections for transferring power from one end of the generator set to the other.

9. In a varying frequency generator set, 5 two alternating current generators, a double rotation motor for driving such generators at varying speeds which periodically rise and fall in alternately recurring periods, and including in the combination means between the generators for transferring power 10 from one end of the set to the other, such means comprising inter-connected gearing.
10. In a varying frequency generator set, two alternating current generators, a double 15 rotation motor for driving such generators

at varying speeds which periodically rise and fall in alternately recurring periods, and including in the combination connections for transferring power from one end of the generator set to the other to equalize 20 the torques exerted by the rotating elements of the motor.

In testimony whereof, I have signed my name at Milwaukee, this 11th day of November, 1919.
